US00D367913S

United States Patent [19]

Hafford et al.

[11] Patent Number: Des. 367,913

[45] Date of Patent: **Mar. 12, 1996

[54] ELECTRONIC INSECT KILLER

[76] Inventors: **Russell J. Hafford; Wilmer C. Hafford**, both of Rte. #1, Box 149, Allagash, Me. 04774

[**] Term: 14 Years

[21] Appl. No.: 30,889

[22] Filed: Nov. 10, 1994

[52] U.S. Cl. D22/123

[58] Field of Search D22/119-123; 43/112-113, 132.1, 98, 99
